CLAIM

The ornamental design for a wire clip, as shown and described.

DESCRIPTION

FIG. 1 is an isometric bottom right view of our wire clip; FIG. 2 is an isometric top left view thereof; FIG. 3 is an isometric top right view thereof; FIG. 4 is a top view thereof; FIG. 5 is a bottom view thereof; FIG. 6 is a left side view thereof; FIG. 7 is a right side view thereof; FIG. 8 is a back side view thereof; and, FIG. 9 is a front side view thereof.

The broken lines are included for the purpose of illustrating portions of the wire clip and form no part of the claimed design.
